[57] CLAIM

The ornamental design for a clamp with neck and flat telephone holder, as shown and described.

DESCRIPTION

FIG. 1 is a perspective view of the clamp with neck and flat telephone holder;

FIG. 2 is a side view of the clamp with neck and flat telephone holder shown in FIG. 1, the opposite side being substantially a mirror image thereof except that the line to the right of the circular features on the clamp would not be seen;

FIG. 3 is a top view of the clamp with neck and flat telephone holder shown in FIG. 2, the bottom being a mirror image thereof;

FIG. 4 is a right end view of the clamp with neck and flat telephone holder shown in FIG. 3; and,

FIG. 5 is a left end view of the clamp with neck and flat telephone holder shown in FIG. 3.

The patterned surface treatment schematically depicted throughout the views is continuous about the surfaces on which it is shown. The neck is shown broken away and connected by broken lines to indicate an indeterminate length. The broken line showing of a tubular member is for illustrative purposes only and forms no part of the claimed design.
